CLAIM

The ornamental design for an electrical power adapter plug as shown and described.

DESCRIPTION

FIG. 1 is a front, top and left side perspective view of an electrical power adapter plug showing a first embodiment of my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front, top and left side perspective view of an electrical power adapter plug showing a second embodiment of my new design;

FIG. 9 is a front elevational view thereof;

FIG. 10 is a rear elevational view thereof;

FIG. 11 is a left side elevational view thereof;

FIG. 12 is a right side elevational view thereof;

FIG. 13 is a top plan view thereof; and,

FIG. 14 is a bottom plan view thereof.

The dash-dot-dash broken lines define the boundaries of the claim and form no part of the claimed design. The equal length broken lines depict environmental structure and form no part of the claimed design.

1 Claim, 14 Drawing Sheets
